UNITED STATES PATENT OFFICE.

LE ROY S. BUNKER, OF WEBSTER CITY, IOWA.

SHEET-METAL RADIATOR.

SPECIFICATION forming part of Letters Patent No. 545,036, dated August 20, 1895.

Application filed February 26, 1895. Serial No. 539,742. (No model.)

To all whom it may concern:

Be it known that I, LE ROY S. BUNKER, a citizen of the United States of America, residing at Webster City, in the county of Hamilton and State of Iowa, have invented Improvements in Sheet-Metal Radiators, of which the following is a specification.

My invention relates to the construction of sheet-metal radiators; and it consists in certain new and useful improvements in a radiator invented by me, and fully described in my application for United States Letters Patent filed February 20, 1894, Serial No. 500,931, whereby a simpler, cheaper, more durable, and lighter radiator is produced.

My invention consists in certain details of construction of the various parts of the radiator, as hereinafter set forth, pointed out in my claims, and illustrated in the accompanying drawings, in which—

Figure 1 is a side elevation of a part of a radiator. Fig. 2 is a sectional view of one of the radiator-sections. Fig. 3 is a sectional view through the line 3 3 of Fig. 2. Fig. 4 is a perspective view of one of the supports. Fig. 5 is a detail sectional view of one of the nuts for holding the sections together.

Referring to the accompanying drawings, the reference-letter A is used to indicate one of the mating side pieces of one radiator-section. Each piece is of an approximately oval shape with its central portion bent inwardly at A², to engage the opposite part and thus form a continuous passage around the edges of the section. Its edges are bent straight outwardly at B, then curved at B² to overlap the outwardly-bent portion, leaving a space between. In the central portion of each end of the part A a circular opening is formed with an annular outwardly-bent shoulder C concentric with the opening. The parts A are formed of stiff sheet metal, and bending the edges together to produce a steam-tight joint has been found quite difficult. I have obviated this objectionable feature by bending the edges, as shown, and then providing a narrow strip of soft flexible metal D and bending its edges over the parts B² and then into the spaces between the parts B and B², and finally firmly pressing the seam thus formed, thereby causing any irregularities in the stiff metal to become embedded into the

softer metal, and thus produce a steam-tight joint.

F indicates a bushing for the openings on the end portions of the section, preferably made of cast metal, with a central opening of smaller diameter than the said opening, an annular flange F² projecting outwardly from one end with its outer surface in engagement with the edges of the opening, and an annular depression F³ in its opposite end. The flange F² and depression F³ are designed to coact with the co-operating features in adjacent sections. In the central portion of each bushing are a number of radial openings H. H² indicate lugs projecting inwardly from the bushings between the said openings, for purposes hereinafter explained. These bushings are placed in position before the two sides of the section are placed together. It is obvious that a number of sections may be placed together with the annular flanges F² on one section entering the depressions F³ on the adjoining section, and when firmly drawn together a tight connection will be produced. To draw these sections together I have provided a perforated pipe J of a somewhat smaller diameter than the opening in the bushings and screw-threaded at both ends. Two of these pipes are used of a length to extend through all of the sections of the radiator, the one at the top and the other at the bottom, in engagement with the lugs H², which serve to keep the pipe concentric within the bushings. For the outer surfaces of the end sections I have provided a nut K, having a central screw-threaded opening adapted to admit the end of the pipe J, and an annular shoulder K², adapted to enter the depression F³. The nuts M for the opposite ends are provided with annular grooves M² instead of the shoulder K², and the lower one for the end where the supply-pipe is admitted has its central bore extended entirely through the nut, thus providing for the admission of the supply-pipe.

For supporting the complete radiator I have provided a device cast complete in one piece and having a groove N in its top adapted to admit the edges of the end section and the integral legs N².

In practical use it is obvious that the steam will freely circulate through all parts of the

radiator, passing from one end to the other through the pipes, and freely circulating through each section through the perforations in the pipes and bushings.

5 Having thus described my invention, what I claim as new therein, and desire to secure by Letters Patent of the United States therefor, is—

10 1. The combination with a sheet metal radiator section of a bushing device, cast complete in one piece having an annular projection on one end and a mating depression on the other, radial openings in its central portion and inwardly projecting lugs between the openings, 15 for the purposes stated.

15 2. A sheet metal radiator, comprising a number of sheet metal sections each having

annular shoulders at its ends and openings in the central portion of the shoulders, a bushing device placed in each end of each section, 20 and resting in said shoulders and each having an annular projection at one end, an annular depression at the other, a central longitudinal opening, a number of radial openings and inwardly projecting lugs, two perforated pipes passed through the central opening of the bushing devices and nuts on the ends of said pipes to hold the sections together, substantially as set forth. 25

LE ROY S. BUNKER.
